UNITED STATES PATENT OFFICE.

ELISHA H. ALVORD, OF SEATTLE, WASHINGTON, ASSIGNOR TO ALVORD AUTOMATIC MACHINE CO., OF SEATTLE, WASHINGTON, A CORPORATION OF WASHINGTON.

PRESS.

1,194,266.

Specification of Letters Patent. Patented Aug. 8, 1916.

Application filed March 29, 1912, Serial No. 687,223. Renewed November 1, 1915. Serial No. 59,150.

To all whom it may concern:

Be it known that I, ELISHA H. ALVORD, a citizen of the United States of America, and a resident of the city of Seattle, in the 5 county of King and State of Washington, have invented certain new and useful Improvements in Presses, of which the following is a specification.

My invention relates to presses, being 10 more particularly designed for operation on pulp used for the manufacture of paper, and has for a primary object the provision of novel mechanism by which moisture is extracted from the material, and further, in 15 the provision of such a construction wherein the material as advanced from the main presser members is constrained for delivery from the press in a desired condition.

Other objects will be set forth as my description progresses and those features of construction, arrangements and combinations of parts on which I desire protection, succinctly defined in my annexed claims.

Referring to the accompanying drawings 25 wherein like numerals of reference indicate like parts throughout: Figure 1 is a top plan, with portions of one of the tension devices broken away. Fig. 2 is an end elevation in partial vertical section. Fig. 3 is 30 a section taken on line 3—3 of Fig. 1. Fig. 4 is a vertical section taken on line 4—4 of Fig. 1, parts being broken away, and Fig. 5 is a fragmentary vertical section illustrating the contracted discharge throat and the 35 main presser members.

Referring to the drawings by numerals of reference, 1 and 1' indicate perforated or foraminous presser members supported for movement to press and simultaneously advance the material to a discharge throat, comprising opposing laterally adjustable side wall sections 2, which wall sections serve as auxiliary presser members tending to further press or to hold the material in 45 its pressed condition, to thereby prevent it from absorbing moisture from the interior of the rolls or from the superimposed body of material being fed.

Presser members 1, 1', which in the 50 present embodiment of my invention are in the form of rolls, each comprises a cylindrical peripheral section supported at spaced points throughout its length on internal annular members 6, to the outer of 55 which said peripheral section is conven-

iently fixed, as by screws 7. Annular members 6 are rigidly carried by suitable arms, fixed to a shaft 5, as shown. Presser members 1, 1' have their shafts 5 journaled in suitable stands 3 and 4 respectively, the 60 latter of which is slidably supported on the supporting frame 8 for movement toward and from the other. For yieldingly holding stand 4 against movement from stand 3, I provide tension devices, now to be described. 65

Reference numeral 9 indicates superimposed rods provided in like arrangement at each end of presser members 1, 1' and each being fixed to a respective one of the stands 3 and 4, as by having screw threaded engagement in an internally threaded lug 12 thereof and provided on its projecting portion with a lock nut 13, and having its opposite or free end portion projecting through and slidably guided in a lug 9' of the opposite stand. On the free projecting end portions of rods 9, springs 10 are arranged and confined between nuts 11 and the adjacent lugs 9'. 70 75

In slidably mounting stand 4, I provide 80 frame 8 with a wear strip or track 14 on which said stand is held for limited movement by bolts 15 which project upwardly through base slots 15' thereof (see Fig. 3).

Throat wall sections 2 which have their 85 upper end portions directed from one another and preferably engaging the presser members 1, 1' to clear the same of clinging material, extend downwardly in diverging paths which are eccentric with respect to the 90 adjacent presser members and are then curved upwardly at the outer sides of said members to provide in conjunction with sections 2 moisture receiving chambers or pans 16, which are provided with suitable end 95 walls 16' and inclined downwardly toward one end portion, having an outlet 17.

Moisture receiving chambers or pans 16 are adjustably carried by screws 30, on 100 swingingly supported carriers consisting of levers 18 fulcrumed on the end portions of shafts 5, the said screws having threaded engagement in the lower end portions of said levers and swiveled in lugs 31 of the pans, by which construction the pans can 105 be adjusted toward and from one another on the said levers, through rotation of the screws which can be effected in any desired manner.

Reference numeral 19 indicates slides 110

mounted for sliding on rods 9 and connected by links 20 each with a pivot lug 18' of a respective lever 18. The movement of slides 19 is limited by shoulders 21, 21' between the latter of which and the adjacent slides, springs 22 are interposed.

Reference numeral 23 indicates a drive pulley fixed to one of the shafts 5 and 24 indicates meshing gears fixed to the shafts 10 5 through which latter the presser members 1, 1' are driven in unison, the teeth of said gears 24 being of suitable depth to remain in mesh during bodily adjustment of presser member 1'.

15 In practice, the material is fed between the presser members 1, 1' from their upper sides and as delivered from their lower sides encounters and is fixed between throat members 2, the said presser members 1, 1' and 20 throat members 2 yielding outwardly independently of one another during this operation, as will be apparent. Moisture extracted from the material through the action of presser members 1, 1' passes into the 25 latter through the apertures in the peripheral portions thereof and finally discharges from their lower side portions into chambers or pans 16.

Having thus described my invention what 30 I claim as new, and desire to secure by Letters Patent of the United States of America, is:—

1. A press comprising opposing presser members supported in opposing relation for 35 movement, means for simultaneously moving said presser members to thereby press and advance the material in the direction of its delivery movement, and an expansible discharge throat for the material arranged 40 at the delivery side of said members to receive the pressed material from the latter and be expanded by said material.

2. A press comprising an expansible discharge throat yieldingly held against expansion, presser members for simultaneously pressing and advancing material through said throat, one of said presser members being supported for movement from the other, and means yieldingly holding 45 said last named presser member against movement from the other.

3. A press comprising a discharge throat having a laterally movable yieldingly held side wall section, opposing rotatable members for advancing material through said throat, and means for rotating said members.

4. A press comprising a discharge throat having a laterally movable yieldingly held 60 side wall section, opposing rotatable members for pressing and advancing material through said throat, one of said members being supported for movement from the other, means yieldingly holding said last 65 named member against movement from the

other, and means for rotating said members.

5. A press comprising a discharge throat having side wall sections yieldingly supported for movement toward and from one 70 another, a rotatable presser member, another presser member associated with said rotatable member for simultaneously pressing and advancing material to said throat for passage therethrough, and means yieldingly 75 pressing one of said presser members toward the other.

6. A press comprising an expansible discharge throat, means yieldingly holding said throat against expansion, and opposing 80 rotatable presser members for advancing material through said throat.

7. A press comprising opposing rotatable presser members, means supporting one of said presser members for movement toward 85 and from the other, means yieldingly holding said last named presser member against movement from the other presser member, and an expansible discharge throat for the material arranged at the delivery side of 90 said presser members and yieldingly restrained against expansion.

8. A press comprising opposing presser members supported for movement, one of said members being foraminous, means for 95 operating said presser members to press the material and simultaneously advance the same in the direction of delivery therefrom, and other presser members opposing one another at the delivery side of said first members and one thereof projecting inwardly between said first named members at the side of the foraminous member.

9. A press comprising opposing rotatably supported presser members having foraminous peripheral portions, means for operating said presser members to press the material and simultaneously advance the same in the direction of its delivery means, and other presser members one of which is yieldingly supported and opposes the other at the delivery side of said first members for reception therebetween of material to the latter, said last named members projecting inwardly between said first named members 115 on opposite sides of the path of delivery therefrom.

10. A press comprising opposing rotatable presser members one of which is supported for bodily movement toward and from the 120 other, other presser members opposing one another at the delivery side of said first named presser member for reception of material therefrom, and means supporting one of said last named presser members for movement toward and from the other independently of movement of said bodily movable first member.

11. A press comprising opposing rotatable presser members, means for rotating 125

5 said members, other presser members arranged in opposing relation at the delivery side of said first members, a swingingly mounted support for one of said last named members, and means yieldingly holding said support against swinging in one direction.

12. A press comprising opposing rotatable presser members, means for rotating 10 said members, other presser members arranged in opposing relation at the delivery side of said first members, means swingingly supporting said last named members for movement toward and from one another, and means yieldingly holding said first means against movement in one direction.

13. A press comprising opposing presser members, means supporting said presser 20 members for rotation, and other presser members arranged at the delivery side of said first members and supported for swinging concentrically to the adjacent first members.

25 14. A press comprising opposing presser members, means supporting said presser members for rotation, presser members arranged at the delivery side of said first presser members, and means supporting one 30 of said last named presser members for swinging concentrically to one of said first members.

35 15. A press comprising opposing rotatable presser members, means supporting said members for rotation, one of said means being slidably supported for movement toward and from the other, a tension device for said slidably supported means, opposing presser members at the delivery side of 40 said first members, means supporting one of said last named members for movement toward and from the other, and a tension device for said last named means combined with said first named tension device and 45 permitting of movement of said last named means independently of said movable first means.

50 16. A press comprising opposing rotatable presser members, means supporting said members for rotation, one of said means being slidably supported for movement toward and from the other, a tension device for said last named means comprising a

spring and a connected rod operatively engaged with said means and with a relatively fixed part, opposing presser members at the delivery side of said first means, means pivotally supporting one of said last named members for movement toward and from the other, a slide member free for 55 movement on said rod and connected with said last named means, and means yieldingly holding said slide member against movement in one direction.

17. A press comprising opposing rotatable presser members movably supported, and moisture receiving pans inclosing the lower portions of said presser members with their opposing wall portions in the path of discharge from said presser members, and means yieldingly holding said pans against movement from one another.

18. A press comprising opposing rotatable presser members having foraminous peripheral portions, and moisture receiving 75 pans inclosing the lower portions of said presser members with their opposing wall portions in the path of discharge from said presser members, one of said pans being yieldingly held against movement from the 80 other.

19. A press comprising opposing rotatable presser members having foraminous peripheral portions, means supporting one 85 of said presser members for movement toward and from the other, and moisture receiving pans inclosing the lower portions of said members and supported for movement toward and from one another.

20. A press comprising opposing rotatable presser members having foraminous peripheral portions, means supporting one 90 of said presser members for movement toward and from the other, moisture receiving pans inclosing the lower portions of 95 said members, and means yieldingly supporting one of said pans for movement from the other independently of said bodily movable presser member.

Signed at Seattle, Washington this 19th 100 day of March, 1912.
